UNITED STATES PATENT OFFICE.

JOSEPH W. DAVIS, OF SAN FRANCISCO, CALIFORNIA.

POCKET-CASE.

1,317,689.

Specification of Letters Patent.

Patented Oct. 7, 1919.

Application filed April 25, 1917, Serial No. 164,418. Renewed February 8, 1919. Serial No. 275,849.

To all whom it may concern:

Be it known that I, JOSEPH W. DAVIS, a subject of the King of Great Britain, residing at San Francisco, in the county of San Francisco and State of California, have invented certain new and useful Improvements in Pocket-Cases; and I do hereby declare the following to be a full, clear, and exact description of the invention, such as will enable others skilled in the art to which it appertains to make and use the same.

This invention relates to pocket cases, and has for its object the provision of a case of this type that will admit of a plurality of 15 different articles such as cigarettes, packages of matches, a mirror and comb being placed and held therein in a novel manner so as to admit of convenient access being had to any of the articles.

Other objects will appear and be better understood from that embodiment of my invention of which the following is a specification, reference being had to the accompanying drawing forming a part thereof, in 25 which:

Figure 1 is a plan view of the case in open position,

Fig. 2 is a longitudinal sectional view taken through the case with the companion 30 members forming the case being in closed position, and

Fig. 3 is a transverse sectional view, taken through the case when in closed position.

Referring to the drawing in detail, the 35 case is shown as comprising a pair of companion rectangular shaped members 1 and 2. Each of the members 1 and 2 has the edges thereof bent laterally and curved, as shown more particularly in Figs. 2 and 40 3 of the drawing, and the edges of one member oppose and engage the edges of the other member when the members are in case formation, as shown in the mentioned figures. Each member has one of the longitudinal 45 edges thereof provided with a plurality of spaced sleeves or knuckles 3, the sleeves or knuckles on one member fitting within the spaces between the sleeve or knuckles on the other member, and a rod 4 extends through the knuckles on the members 1 and 2 and 50 coöperates therewith to complete a hinge for connecting the members 1 and 2 to each other. A cigarette container is located at the point of connection between the members 1 and 2 and is formed of a pair of spaced plates 6 and 7, each being formed of

flexible metal, and the said plates 6 and 7 are provided with opposed outward depressions 9, which coöperate to provide individual compartments for the cigarettes. The opposing ends of the plates 6 and 7 have sleeves or knuckles 10 formed thereon and the opposite ends of the rods 4 are bent upwardly, as at 11, and extended through the knuckles 10 on the adjacent ends of the plates 6 and 7, so as to connect the plates 6 and 7 to each other. Extending longitudinally of the inner face of the member 1 is a strip of resilient metal 12, which is centrally provided with a depending flange 13, which has suitable connection with the inner face of the member 1, and the opposite ends of the strip 12 are bent in the direction of the member 1, as shown at 14, and thence terminally bent laterally, as at 15, to provide flanges which 75 are suitably connected to the inner face of the member 1. The flange 13 and the inwardly bent portions 14 serve as spacing elements for holding the strip 12 in spaced relation with the inner face of the member 1, and the said strip 12 is slightly curved inwardly, as shown at 16, and on opposite sides of the flange 13 to provide resilient gripping surfaces which coöperate with the inner face of the member 1 for clamping 80 therebetween a match package, designated A. Located on the inner face of the member 1, and adjacent the free longitudinal edge thereof, is a pair of spaced clips each of which includes a portion 17, which extends 85 in parallelism with the inner face of the member 1 and an angular portion 18, which extends in the direction of the inner face of the member 1 and is terminally bent to provide a flange 19, which is adapted to have 90 connection with the inner face of the member 1 in any suitable manner. The angular portions 18 on the clips serve as spacing elements for the portions 17 from the inner face of the member 1, so as to admit of the teeth 95 of a comb, designated B, engaging beneath the portion 17 of the clips. The free ends of the portions 17 are deflected outwardly, as at 20, to permit of the engagement of the teeth beneath the portions 17 to be facilitated. A clip 21 is located adjacent the strip 12 and in line with the space between the clips that engage over the comb teeth, and is provided with a pair of ears, which 100 extend between a pair of ears 22 mounted on the inner face of the member 1, and a pin 23 extends through the ears 22 and the 105 110

ears on the clip 21 so as to pivotally connect the clip 21 to the ears 22. The clip 21 has one end thereof curved, as shown at 24, and adapted to engage over the back of the comb 5 B, and the opposite end of the clip is bent upwardly, as shown at 25, to provide a manipulating portion whereby the curved end 24 of the clip may be raised from engagement with the comb when it is desired to 10 move the latter from the member 1. A coil spring engages around the pin 23 and has one terminal thereof extending over the clip 21, as shown at 26, so that the curved end 24 of the clip will lie in tight engagement 15 with the back of the comb B.

A mirror 27 is mounted on the inner face of the member 2 and is held in place by means of a plurality of clips 28. The clips 28 are located at the respective corners of 20 the member 2 and each clip consists of a portion 29, which engages the outer face of the mirror, and an angular portion 30 that extends in the direction of the member 2 and is terminally provided with an attaching 25 flange 31, which is secured to the member 2 in any suitable manner.

The member 2 of the case has the free longitudinal edge thereof provided with a resilient clip which includes a shank 32 se- 30 cured to the inner side of the edge of the member 2, and a circular head 33 that has a portion thereof projecting through a slot in the adjacent curved edge of the member 2, the inner portion of the head having an 35 aperture 34 therein adapted, when the companion members 1 and 2 are in closed position, to receive a stud 35 mounted on the inner side of the curved edge of the mem- ber 1, so as to hold the members 1 and 2 in 40 position, as shown in Fig. 3. The rod 4 has

a coiled spring 36 mounted thereon, at a medial point, the said spring being inter- posed between certain adjacent knuckles 3, and the terminals of the spring are secured, respectively, to the companion members 1 45 and 2 of the case. When the members 1 and 2 are in case formation, as shown in Fig. 3, the spring 36 will be tensioned so that when the circular head 33 of the clip is moved inwardly so as to withdraw the head 50 from engagement with the lug 35, the spring 36 will exert an opening force on the members 1 and 2 and move the same to open position.

It is evident that various changes might 55 be resorted to in the form, construction and arrangement of the several parts without departing from the spirit and scope of the invention as claimed.

Having thus described my invention what 60 I claim as new, is:

A pocket case including a pair of hingedly connected members, a strip of resilient metal extending longitudinally of the inner side of one of the members, said strip provided centrally on its under side with a depending flange for engagement with the inner side of the member to space the strip therefrom and the ends of the strip which are spaced from said member being curved inwardly in the 70 direction of the member to provide resilient clamping members and the terminals of the strip being secured to the inner side of the said member.

In testimony whereof I affix my signature 75 in presence of two witnesses.

JOSEPH W. DAVIS.

Witnesses:

E. J. CASEY,

RAYMOND J. CASEY.
